UNITED STATES PATENT OFFICE.

JOSEPH GOULET, OF TIMMINS, ONTARIO, CANADA, ASSIGNOR OF ONE-HALF TO
ALBERT BRAZEAU, OF TIMMINS, ONTARIO, CANADA.

AUTOMATIC SAFEGUARD.

Application filed June 2, 1923, Serial No. 643,122. Renewed December 28, 1925.

To all whom it may concern:

Be it known that I, JOSEPH GOULET, a citizen of Dominion of Canada, and resident of Timmins, in the district of Cochrane and 5 Province of Ontario, Dominion of Canada, have invented certain new and useful Improvements in Automatic Safeguards, of which the following is a specification.

This invention relates to safety devices 10 and particularly to a device which would be used in connection with a mine cage.

The primary object of my invention is to provide an automatic operated member which will be in operative position when the 15 cage is even with one of the levels in the mine and which will be in operative position when the cage is either above or below the level referred to.

With the foregoing and other objects in 20 view as will appear as the description proceeds, the invention consists in the novel construction, combination and arrangement of co-operating elements as hereinafter more specifically set forth, claimed and shown in 25 the accompanying drawings forming a part of the present application, in which:

Fig. 1 is a side elevation of a mine shaft looking at the same from the side, dotted lines indicating the position of the mechanism when the cage is in the position as indicated by dotted lines.

Fig. 2 is a sectional view taken on line 2—2 of Fig. 1.

Fig. 3 is an enlarged detail view of one 35 of the stop members.

Fig. 4 is an enlarged detail view of the method of hinging the lift plates.

5 indicates the corner timbers commonly used in framing a mine shaft. 6 indicates 40 the guide timbers, 7 indicates the cage having side guide channels 8.

The cage 7 is provided at its opposite sides with curved channel members 9 having flared upper and lower ends as more particularly illustrated in Fig. 1. These curved channel members are suitably bolted or riveted onto the side brace members of the cage as at 10.

At each level I provide oppositely positioned side braces or plates 11 which are suitably engaged between one of the corner timbers and one of the guide timbers. These side plates 11 are provided with the longitudinal slots 12.

55 13 and 13' indicate fulcrum plates suit-

ably attached to the corner timbers 5 and extending inwardly thereof. 14 and 14' are levers fulcrumed on the plates 13 and 13', the levers 14 and 14' being connected respectively at their lower and upper ends to the link 15. The lever 14 also has its upper end connected to the link 15. The inner or free end of the link 15 is provided with a guide wheel 17 extending inwardly therefrom and a guide block 18 extending outwardly therefrom. The guide wheel 17 will be operated by the curved channel member 9 as the said channel member passes up and down in connection with the cage 7. The relative position of the channel member 9 and the guide wheel 17 is clearly illustrated in Fig. 2. The guide block 18 reciprocates in the longitudinal slot 12 in the side plate 11. If the lever has tracks entering from the opposite sides of the cage the mechanism including 75 the levers 14 and 14' at the opposite sides of the cage will be operated at the opposite sides or entrances to the shaft.

19 illustrates a platform preferably made from channel iron. Riveted at the inner corners of this channel iron are hinge pin receiving members 20. The corner timbers 5 are provided with plates 21 counter-sunk into the corner timbers, as clearly illustrated in Fig. 3. The plates 21 are provided with hinge pins 22 supported therein by any suitable method. The plates 11 are provided with an inwardly extended flange 23, the purpose of which will hereinafter be described. The platform 19 is provided with suitable eye bolts 24 which eye bolts are hingedly connected with the links 16. The corner timbers are vertical when in their proper position and the flanges 23 are set at an angle so that when the platform 19 is 80 hinged upwardly the top of the same will be tilted inwardly and thus remain in that desired position until forced back to operative position by the link 16.

Having described the working mechanism 100 I will now describe the operation. The curved channel members 9 travelling up and down with the cage 7 will at each level engage with the guide wheels 17. When the cage travels either up or down from any vertical level it will leave the guide wheels at the outer end of the longitudinal slot 12 so that when the cage comes back to this level the curved channel members 9 will move the guide wheels 17 to the position as indicated 105 110

in Fig. 1. Through the link 15, the lever 14 will be fulcrumed to move the link 16 outwardly. By the link 16 moving outwardly the platform 19 is hinged downwardly. As soon as the cage moves either up or down from the level the platform 19 will be hinged back to rest against the flanges 23 in an upright angular position.

The guard rods 28 are carried by the platform 19. The inner ends of the guard rods are riveted to the platform 19 while the free ends extend in a vertical position when the platform is in its normal position. These guard rods will act in place of the usual gate or bar.

While the platform 19 is in this position it will serve as a stop or guard to the entrance of the shaft and when the platform 19 is in a horizontal position it will act as an entrance platform to the cage. If the cage is to be used for hoisting mine cars it will be provided with suitable tracks 24 and the different levels will be provided with suitable tracks 25. When the cage 7 is in its upper position at any desired level the tracks 24 will be in alignment with the tracks 25. The platform 19 may be suitably grooved transversely or be provided with pairs of plates 26 which plates 26 will form a groove between them which groove will be in alignment with the inside of the tracks 24 and 25 so that a mine car passing from either of the rails 24 or 25 will be guided by the flange on the mine car wheels running in the groove between the plates 26.

The rest of the mechanism for operating the platform 19 will be the same as that thereinbefore described.

While the preferred embodiment of the invention has been disclosed, it is to be understood that minor changes in the details of construction, combination and arrangement of co-operating elements may be resorted to within the scope of what is claimed, without departing from the spirit of the invention.

What I claim as new is:

1. A safety device for an open shaft, comprising an entrance platform hingedly

mounted at the entrance to said open shaft; a mechanism for turning said entrance platform from its normal vertical position to a horizontal operative position and returning it to its normal position; an elevator cage adapted to reciprocably operate in said open shaft; and a means carried by said cage adapted to operate said mechanism.

2. A safety device for an open shaft, comprising an entrance platform hingedly mounted at each entrance to said open shaft; a mechanism for turning said entrance platforms from their normal vertical position to a horizontal operative position and returning them to their normal position; an elevator cage adapted to reciprocably operate in said open shaft; and a means carried by said cage adapted to operate said mechanism.

3. A safety device for an open shaft, comprising an entrance platform hingedly mounted at the entrance to said open shaft; a mechanism for turning said entrance platform from its normal vertical position to a horizontal operative position and returning it to its normal position; an elevator cage adapted to reciprocably operate in said open shaft; a means carried by said cage adapted to operate said mechanism; said cage having tracks thereon; tracks up to the entrance to said shaft; suitable grooves on said platform to act as guides between said tracks when said platform is in horizontal operative position.

4. A safety device for an open shaft, comprising an entrance platform hingedly mounted at the entrance to said open shaft; a mechanism for turning said entrance platform from its normal vertical position to a horizontal operative position and returning it to its normal position; an elevator cage adapted to reciprocably operate in said open shaft; a means carried by said cage adapted to operate said mechanism; and guard means carried by and extending from said entrance platform.

In testimony whereof, I affix my signature.

JOSEPH GOULET.
